(57) **CLAIM**

The ornamental design for a trivet, as shown and described.

DESCRIPTION

FIG. 1 is an isometric view of the trivet;

FIG. 2 is a top plan view of the trivet of FIG. 1;

FIG. 3 is a bottom plan of the trivet of FIG. 1; and

FIG. 4 is a side view of the trivet of FIG. 1; the opposite side being the same; and,

FIG. 5 is an end view of the trivet of FIG. 1; the opposite side being the same.

The cross-hatching on the surface of the invention is understood to represent a texture that continues across entire surface.
